UNITED STATES PATENT OFFICE.

SIMEON G. PHILLIPS, OF PERTH AMBOY, NEW JERSEY.

LAWNING AND CLEANING CLAY.

SPECIFICATION forming part of Letters Patent No. 252,796, dated January 24, 1882.

Application filed November 8, 1881. (No model.)

To all whom it may concern:

Be it known that I, SIMEON G. PHILLIPS, of Perth Amboy, Middlesex county, in the State of New Jersey, have invented certain new and useful Improvements Relating to Lawning and Cleaning Clays, of which the following is a specification.

The invention may be used either alone or in connection with the means set forth in a patent issued to me, dated November 30, 1880, No. 235,014, for washing clay and separating certain impurities by virtue of their greater coarseness or specific gravity than the fine and valuable clay.

My present invention serves to separate foreign matter or impurities by a different principle—the inability of large masses to move through a fine fabric which will easily permit the passage of the fine clay properly worked up with water. In other words, I strain the clay and remove from it all the material which will not pass through the strainer. Uniformly-woven silk is the material I employ for the strainer. Such has been long approved for this purpose, but as heretofore worked it becomes rapidly clogged. I mount the fabric on a slowly-rotating frame, forming a hollow wheel or bolt with one end open. Into this I introduce the clay-slip continuously through a spout in such a manner that the screen is kept clear of accumulation of the coarser particles and avoids clogging. The water, with the fine clay, passes rapidly through the fabric and falls into a spout or tank beneath, to be subsequently outlined.

The coarse particles which do not pass the fabric remain, with a small quantity of the water, on the interior of the fabric, and are by the revolution of the wheel carried slowly around. I introduce into the interior of the wheel a shallow spout nearly as wide as the interior of the wheel will contain, and extend it in at the open end with an inclination outward. I apply a liberal quantity of pure water on the outside of the fabric in the upper portion of the rotation. This water moves inward through the fabric and falls into the internal spout, carrying with it all the remaining coarse matter, and leaves the fabric perfectly clean to receive on its descent a fresh charge of clay to be strained. Thus the opera-

tion repeats itself continuously. The foreign matter falling from the top of the interior into the internal spout is carried away by the water and is allowed to waste.

The accompanying drawings form a part of this specification, and represent what I consider the best means of carrying out the invention.

Figure 1 is a longitudinal section of the main parts of the apparatus. Fig. 2 is a front elevation, partly in section. Fig. 3 is a side elevation of the entire apparatus on a smaller scale. Fig. 4 is a front elevation of the same. Fig. 5 is a rear elevation of the framing, and Fig. 6 is a plan view of the stationary parts of the apparatus.

Similar letters of reference indicate like parts in all the figures.

A is a tilting frame turning on fixed supports *a* and forming finished bearings for the shaft B. C' C² C³ is a framing of wood or other suitable material, the parts C' being arranged radially as the spokes of a wheel, the parts C² circumferentially and the parts C³ longitudinally of the wheel. The parts C³ lie parallel to the shaft B. The spokes C' are omitted at one end, the framing being stiffly supported by the remaining parts C'.

D is a covering of uniformly-woven silk. I employ No. 15 and strain the material very finely.

E is a spout, which leads in the clay-wash to be strained and pours it in the interior of the structure at the point represented in Fig. 2.

G is a broad shallow spout extended into the open end of the revolving strainer at an inclination, as indicated in Fig. 3.

H is a spout bringing pure water from a pump or elevated reservoir (not represented) and showering it upon the exterior of my strainer in the upper part of its course.

I is a tank below, which receives the strained material.

K' is a smooth pulley fixed on the shaft K, which is held in fixed bearings, and rapidly revolved by any suitable means. (Not shown.) The circumferential part C² adjacent is smoothly turned, and applies thereto when the frame A is properly tilted by applying the weight L, or otherwise. The friction of the pulley K' 95 100

- causes the proper slow revolution of my strainer. When it is desired to discontinue the operation the wash is shut off from the spout E and the pure water is shut off from the pipe H.
- 5 Then the revolution of the strainer is discontinued by simply disengaging the weight L and allowing my strainer to descend by gravity out of contact with the pulley K'. The spout E, through which the thin clay-wash is received, is directed much to one side, so that the stream falls on a greatly-inclined surface of the strainer, and moves downward thereon faster than the strainer moves in the same direction. In other words, the thin fluid not only moves through the meshes of the strainer, but also moves parallel thereto. This motion tends to wash the strainer and prevent its clogging with the coarse particles. I attach much importance to this.
- 20 In the operation of the invention the water moving inward through the fabric D in the upper part of the strainer, effectually cleans it of all impurities. When, by the continued rotation of the device, a portion thus cleaned is brought to receive the current of fine clay-wash entering through the pipe or spout E, it allows the fine clay to pass very promptly. The impurities accumulating on the inner face of the fabric D may retain a little of the fluid, but 25 with the proper slow revolution nearly all the clay-wash will move through the fabric and drop from the outside. The thick matter adheres more or less perfectly to the interior of the fabric until it is carried up over the spout G, when it falls into said spout. This fall is promoted by the water applied from the pipe H outside.
- It is important that the water from the pipe H be applied so liberally as to not only cause 30 the coarse matter to fall by gravity, but also to strongly wash through the interstices of the silk and leave them entirely clean. All the impurities with the water received are carried away by the spout. The pure clay accumulates 35 in the tank I, and is subsequently allowed to settle and pressed to remove as much of the water and of the soluble matter contained therein as possible. It is then ready to be stored or shipped for use.
- 40 50 Modifications may be made in the details

without departing from the principle of the invention. I can lawn by this method and by this apparatus clay of wide range of qualities and for various purposes.

One of the uses for which I esteem this screening to be particularly well adapted is the preparation of fine clay for incorporation in paper, or for preparing the surfaces of paper. It is also well adapted for preparing fire-clay by the removal of particles of iron or other material, which are deleterious.

I claim as my invention—

1. The strainer D, mounted on a suitable open-ended framing capable of being revolved, in combination with means E for introducing the fluid to be strained, provisions I for receiving the strained fluid, and an internal receptacle or spout, G, arranged to receive the material which cannot pass through the strainer, substantially as herein specified. 70

2. The driving-shaft K and wheel K', in combination with the tilting frame A a, and with the revolving strainer D, mounted on a suitable frame, C' C² C³, with provisions for supplying and taking away the fluid and provisions 75 G for receiving the material which cannot pass the strainer, all arranged for joint operation substantially as herein specified.

3. The means H for supplying water to the upper side of the strainer D, so as to move 80 through the same in the opposite direction to that of the straining, in combination with provisions for straining in another part of the revolution, and with a spout, G, for taking away the retained material, as herein specified. 85

4. The method herein described of lawning and cleaning clay, consisting in projecting the slip in a stream against a strainer in an inclined position, so that the action of the stream urges the coarser particles along on the surface of 90 the strainer and keeps the acting part of the latter clear, substantially as herein specified.

In testimony whereof I have hereunto set my hand at New York city, New York, this 18th day of October, 1881, in the presence of 95 two subscribing witnesses.

SIMEON G. PHILLIPS.
